R. J. BARTHOLOMEW ET AL

LET-OFF FOR LOOMS

Filed Sept. 11, 1926

Robert J. Bartholomew, Inventor.
Robert Langet, BY
Kiddle and Margeson, ATTORNEYS.

UNITED STATES PATENT OFFICE.

ROBERT J. BARTHOLOMEW, OF LANSDALE, AND ROBERT LAUTER, OF PHILADELPHIA, PENNSYLVANIA, ASSIGNEES TO FLETCHER WORKS, INCORPORATED, OF PHILADELPHIA, PENNSYLVANIA, A CORPORATION OF PENNSYLVANIA.

LET-OFF FOR LOOMS.

Application filed September 11, 1928. Serial No. 134,775.

This invention relates to an improvement in looms, and has for one of its objects the provision of an improved letoff.

A further object of our invention is the provision of a letoff in which the maximum tension may be exerted on the warp with the minimum in weights on the letoff levers.

A still further object of our invention is the provision of a letoff in which the brake tension may be regulated at will within close limits and with the minimum of effort.

Another object of our invention is the provision of a letoff structure in which the brake bands are quickly detachable, thereby enabling an empty beam to be quickly removed and replaced with a full one.

In the accompanying drawing we have illustrated, somewhat diagrammatically, an embodiment of our invention.

Referring to this drawing in detail, 1 designates a partially filled warp beam, the warp carried thereby being designated 2.

3 designates weighted let-off levers carrying the tension weights 4. These levers will be arranged in pairs and are pivoted at 5. Each lever carries a roller 6 at the extremity of its short arm 7, the weights 4 being carried at the extremity of the long arm 8 of the lever, or these weights may be carried on the tie rods 8' by which the levers are tied together.

Cooperating with the beam 1 are two brake bands 9, one end of each band being anchored at 10. These brake bands may be of steel, rope, or other suitable material, and preferably lie in grooves on the warp beam heads.

The free ends 11 of the brake bands are connected to each other by a rod 12 extending lengthwise of the warp beam, being attached to this rod by a quick detachable link-pin connection. This connection comprises a link or rod end 13 having one end threaded for a nut 14 for adjustment, and its other end being provided with a hole for the pin 21. This pin passes through both the rod end 13 and the eye in the free end 11 of the brake band, and may be quickly removed to permit of removal of an empty beam and the insertion of a full beam.

Intermediate weighted let-off levers 3, and the free ends of the brake bands are levers 15. These levers are pivoted at 16 and tied together by the rods 17 and 18. The intermedi-

ate levers 15 are bell crank levers and each comprises a long arm 19 adapted to engage with the rollers 6 on the letoff levers, and a short arm 20 which carries the tie rods 17 and 18.

The warp 2 is led off from the beam 1, passes beneath the tie rod 17, over the rod 12 which, as above mentioned, is attached to the brake bands 9, and then beneath the tie rod 18, from whence it is led to the takeup, not shown, at the front of the loom. The pull of the takeup, as will be obvious, tends to lift the short arm 20 of the intermediate levers 15 into engagement with the rod 12, to ease off on the brake band 9, the long arm of these levers pushing downwardly on the rollers 6 carried by the short arm 7 of the levers 3. This tends to raise the long arm of these levers, this tendency being resisted by the weights 4. As the beam lets off the short arm 20 moves away slightly from the rod 12 to keep the warps under proper tension.

It will be apparent from the foregoing that we have provided a compound leverage system between the brake bands 9 and weights 4 whereby maximum tension on the brake bands is obtained with the minimum in weights on the letoff levers. It will also be apparent that this arrangement permits of the tension on the brake bands being regulated at will within quite close limits.

While we have described a specific embodiment of our invention, it is to be understood that the same may be varied within the spirit and scope of our invention, as, for example, if desired, the rollers 6 may be replaced with gear teeth to obtain rolling contact between the levers 3 and 19.

What we claim is:

1. In a loom, the combination of a warp beam, a brake therefor, a bell crank lever, the warp on the brake beam being operatively connected to said lever and brake, a letoff lever operatively connected to said first mentioned lever, the two levers providing a compound lever system, and a weight carried by the letoff lever.

2. In a loom, the combination of a warp-carrying beam, a brake therefor, a lever pivoted intermediate its ends, one end of said lever being operatively attached to the warp and brake, a letoff lever to which the opposite end of the first mentioned lever is operatively

connected, and a weight on the end of the let-off lever opposite the end which is connected to the first mentioned lever.

3. A let-off for looms, comprising in combination a warp beam, a brake therefor, a weighted let-off lever, an intermediate lever, a rod attached to the brake and separate from the intermediate lever, the warp on the warp beam being operatively connected to the intermediate lever and said rod, the intermediate

lever cooperating with the weighted let-off lever to control through said rod the action of said brake on the warp beam.

This specification signed this 8th day of September, 1926.

ROBT. J. BARTHOLOMEW.

This specification signed this 8th day of September, 1926.

ROBERT LAUFER.
